UNITED STATES PATENT OFFICE

JAMES ROSS MITCHELL, OF MONTPELIER, VERMONT

EMERY OR ABRADING WHEEL

Application filed April 30, 1931. Serial No. 534,037.

This invention relates to abrading or polishing devices designed primarily for polishing stone, although it may be employed for other polishing operations.

5 The primary object of the present invention is to provide an emery polishing wheel of the character wherein the abrasive is fed through the center thereof, which is made up of a plurality of segmental annuli of a novel design which causes the abrasive to be fed to the under surfaces thereof between the same and the surfaces of the body being polished.

10 A further object of the invention is to provide a polishing wheel made up of a plurality of segmental annuli, in which the segments of each annulus are spaced apart and the spaces between the segments of the group of annuli are out of alignment radially of the wheel so as to prevent the too rapid passage of the abrasive from the center of the wheel to the outer edge thereof.

15 A still further object of the invention is to provide a novel means for directing the abrasive circumferentially as it passes between the segments of one annulus to those of the adjacent annulus so that a portion thereof will be fed beneath the annulus segments.

20 A still further object of the invention is to provide a wheel of the above described character in which each segment of each annulus is formed at one end to provide a receiving mouth into which the abrasive is directed from the end of the adjacent segment, so that 25 a greater quantity of the abrasive will be worked between the annuli of the wheel and the body being polished than normally gets into this position under wheels of the character in common use.

25 The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient fea-

tures of the invention as expressed in the appended claims.

In the drawing:

Figure 1 is a view in bottom plan of the abrading wheel embodying the present invention;

Figure 2 is a sectional view taken on the line 2—2 of Figure 1;

Figure 3 is a sectional view taken on the line 3—3 of Figure 1; and

Figure 4 is a side elevational view of the wheel, showing attached thereto the structure by which the wheel is connected with mechanism for rotating it.

Referring now more particularly to the drawing wherein like numerals of reference designate corresponding parts throughout the several views, the numeral 1 indicates generally the emery or abrasive wheel embodying the present invention. This wheel is made up of an outer annulus 2 and a series of inner annuli each of which is indicated generally by the numeral 3. All of these annulae are in spaced relation.

Each annulus 3 is divided into a number of segments, each of which is indicated by the numeral 4, those illustrated being separated into four segments. Each segment 4 has one end formed to provide a vertical wall portion 5 of ogee curvature, this surface terminating at the end of the segment, preferably inwardly slightly from the outer or convex face thereof. At its other end, each segment 4 has its bottom corner rounded off as indicated at 6 and has formed in the under face across this rounded corner or end 6 the mouth 7. These mouths 7 are in the form of channels cut at an inclination across the rounded end of the segment, starting adjacent the top thereof and curving inwardly and downwardly to come out through the bottom face of the segment at a substantial point inwardly from the end. It will thus be seen that each segment has the curved, reduced feeding end which is formed by the vertical wall portion 5, disposed adjacent and in spaced relation to the mouth 7 formed in the end of the adjacent segment.

Each of the segments of each annulus 3 is struck from a different center, in the present

case each annulus is divided into four segments, the radial centers thereof form the corners of an imaginary square at the center of the wheel. By locating the radial center of each segment at a different point from the others, the reduced or feeding ends of the segments are directed toward the center of the mouth of the adjacent segment.

As previously stated, the adjacent ends of the segments of each annulus are in spaced relation to provide a passageway for some of the abrasive material to pass through toward the periphery of the wheel. In order to prevent the material from passing too rapidly from the center of the wheel outwardly, and also to cause it to strike the curved feeding or guide faces 5 of the segments so that a portion thereof will be directed from these faces into the adjacent segment mouths 7, the segments are arranged with the passages between the ends thereof out of alignment radially of the wheel.

The outer or terminal annulus 2 has formed in the inner wall thereof a series of pockets 8 and one end of each of these pockets forms a vertical wall 9, the lower edge of which is rounded similar to the rounded edge 6 of each of the segments, and this rounded surface has a channel formed therein which forms a mouth 10 which opens through the bottom face of the annulus at a point removed from the wall 9. It will thus be seen that all of the abrasive material which passes radially outwardly through the passages between the spaced ends of the segments 4, will finally collect against the inner wall of the unbroken outer annulus or terminal annulus and will find its way into the pockets 8 from which it will be guided into the mouths 10 to be fed therefrom between the bottom face of the annulus and the surface of the stone body or other body being polished.

The annuli making up the present abrasive wheel may be mounted in any suitable manner. In illustrating the invention these annuli are mounted upon four supporting plates, each of which is indicated by the numeral 11, and which are disposed radially of the wheel across the passages between the ends of the segments. It will of course be understood that this is only one of a number of ways in which the annuli may be mounted and the invention is not to be limited to this specific construction.

It will also be understood that the segmental annuli may be employed in any number, the number being regulated by the diameter of the wheel. The height or thickness of these annuli is also determined by the size of the wheel of which they form a part. Wheels of this character are employed in a variety of sizes ranging from six to eighty-four inches in diameter.

From the foregoing description it will be readily seen that with a wheel constructed in

accordance with the present invention the passage of the abrasive material which is introduced through the center of the wheel will be much slower from the center to the outer rim of the wheel due to the manner in which the passages between the segments are located than in wheels of the character at present in use and in addition to this, more of the abrasive material passing through these passages will find its way under the segments because of the curved guide pieces at the ends thereof and the abrasive material receiving mouths adjacent these surfaces.

Having thus described the invention, what is claimed is:—

1. A polishing wheel of the character described, comprising a series of annular members of graduated sizes and disposed in spaced relation in the same plane, each of said members being divided into a plurality of segments, means formed in one end of each segment and opening through the working face thereof, for receiving an abrasive, the end of the adjacent segment directed toward said means being formed to guide abrasive material to the said means, and a terminal annulus surrounding the segmental annuli.

2. An abrasive wheel of the character described, comprising a plurality of segmental annuli each having a mouth formed in one end and opening through the working face thereof, and each further having its inner surface at the other end cut away to form a curved wall, the segments of each annulus being in spaced relation and having the tapered ends thereof directed toward the centers of adjacent mouths.

3. An abrasive wheel of the character described, comprising a plurality of segmental annuli each having a mouth formed in one end and opening through the working face thereof, and each further having its inner surface at the other end cut away to form a curved wall, the segments of each annulus being in spaced relation and having the tapered ends thereof directed toward the centers of adjacent mouths, the spaces between the segments of each annulus providing passages for the movement of abrasive material radially of the wheel, and said passages being arranged in staggered relation radially of the wheel to hinder the passage of the abrasive material toward the periphery of the wheel.

4. An abrasive wheel of the character described, comprising a series of segmental annuli arranged one within the other and in spaced relation and having flat abrading surfaces disposed in the same plane, the segments of each annulus being spaced apart to provide abrasive passages, means at one end of each segment for directing abrasive material circumferentially thereof toward the adjacent end of the adjacent segment, and means for gathering abrasive material beneath the said adjacent end of the adjacent

segment to direct the same beneath the abrading surface of the segment and a body of work.

5 5. An abrasive wheel of the character described, comprising a plurality of segmental annuli of graduated sizes, arranged one within the other and having flat abrading surfaces disposed in the same plane, the segments of each annulus being in spaced relation to provide an abrasive material passage therebetween, each segment having one end formed with a vertical wall of ogee curvature to provide the same with a tapered abrasive guide surface, the other end of each 10 segment having the bottom corner rounded and having the rounded surface provided with an abrasive receiving mouth opening through the flat abrading face thereof, said segments of each annulus having different 15 radial centers to direct the tapered abrasive guiding end toward the center of the adjacent abrasive receiving mouth, and said abrasive passages being out of alignment radially 20 of the wheel to hinder the radial passage of the abrasive material.

25 6. An abrasive wheel of the character described, comprising a plurality of segmental annuli of graduated sizes, arranged one within the other and having flat abrading 30 surfaces disposed in the same plane, the segments of each annulus being in spaced relation to provide an abrasive material passage therebetween, each segment having one end formed with a vertical wall of ogee curvature to provide the same with a tapered abrasive 35 guide surface, the other end of each segment having the bottom corner rounded and having the rounded surface provided with an abrasive receiving mouth opening through 40 the flat abrading face thereof, said segments of each annulus having different radial centers to direct the tapered abrasive guiding end toward the center of the adjacent abrasive receiving mouth, and said abrasive 45 passages being out of alignment radially of the wheel to hinder the radial passage of the abrasive material, and a terminal annulus surrounding the segmental annulae and having its inner surface provided with a plurality 50 of abrasive receiving pockets each having a straight end wall and an abrasive receiving mouth opening through said end wall and through the abrading face of the annulus.

55 7. A grinding wheel having radially spaced grinding members, with the inner side wall of one grinding member shaped to provide pockets to receive abrasive, the extreme inner edge portion of the side wall 60 forming each pocket being hook-shaped and being projected forwardly.

In testimony whereof I hereunto affix my signature.

JAMES ROSS MITCHELL.
